INC. ATTORNEYS.

UNITED STATES PATENT OFFICE.

JAMES V. WASHBURN, OF FULTON, NEW YORK.

FASTENING DEVICE.

Application filed March 29, 1921. Serial No. 456,765.

To all whom it may concern:

Be it known that I, JAMES V. WASHBURN, a citizen of the United States, and a resident of Fulton, in the county of Oswego 5 and State of New York, have invented a certain new and useful Fastening Device, of which the following is a specification.

The invention relates to fastening devices, particularly of the type which include a pair 10 of opposed jaws or members connected at one end and adapted to be clamped over the sheets of paper or other material which are to be fastened together and has for its object to provide a fastening device of this type in 15 which the jaws fold relatively to the connecting member along independent lines spaced from each other to provide a relatively wide bend for the accommodation of said sheets without causing said jaws to 20 diverge toward their free ends. Other objects of the invention will appear from the description hereinafter and the features of novelty will be pointed out in the appended claims.

Reference is to be had to the accompanying drawings which illustrate examples of the invention without defining its limits and in which Figure 1 is a plan view of one form of my fastener; Fig. 2 is an elevation thereof; Fig. 3 is a sectional view through the fastener, sheets of paper being shown as held by the fastener; Fig. 4 is a perspective view of the fastener; Figs. 5 and 6 are perspective views of other forms of my fastener; Figs. 35 7, 8 and 9 are blanks of the fastener shown in Figs. 4, 5 and 6; and Fig. 10 is a perspective view of the preferred form of fastener.

This fastening device comprises generally, 40 two members or jaws which face each other and extend in the same direction from an end member whereby said jaws are connected at one end, the other or free ends of said members being compressible toward each other, and the jaws or members being connected to the end member in such a manner that each folds along its own folding line relatively to the end member; that is, the jaws fold relatively to the end member 45 along independent, substantially parallel lines spaced from each other. One of the members or jaws is preferably provided with a punch or prong projecting toward the other, in which case the other jaw or member has a perforation for receiving the punch 50 or prong.

The fastening device or fastener, as devices of this character are generally known, is preferably stamped or struck up from a sheet metal blank 1 to form the jaws or members 2, 3 which face each other and extend in the same direction from an end member 4 whereby said jaws are connected at one end, the jaws being foldable relatively to said end member along independent lines 5, 6 respectively, said lines 5 and 6 being spaced apart in substantially parallel relation, as shown in the drawings.

In order to automatically predetermine or define these folding lines 5, 6 the fastener 70 may be weakened along parallel lines at the bases of the jaws 2, 3, that is, at the junc- tures of the jaws and the end member 4. Thus, as shown in Figs. 1 to 4 inclusive and in Fig. 10, the fastener may be weakened by 75 providing recesses 8 in the form of perforations of rectangular, triangular or other shape in the fastener near the end member 4 or, as shown in Figs. 5 and 8, by forming equivalent recesses in the form of square 80 notches 9 in the edges of the fastener near said part; in Figs. 6 and 9, the folding lines are defined by corresponding recesses in the form of V-shaped notches 10 located in pairs at opposite edges of said fastener. In any 85 case, what may be termed a folding bar is provided upon which the jaws are positively and automatically bent. It will be under- stood that the above are only examples and that the device may be constructed in any 90 other suitable manner whereby the folding lines are defined in the predetermined man- ner. By reason of the two lines of fold 5, 6, a relatively wide bend is provided so that when the fastener is attached to sheets of 95 paper or other material, the jaws will either lie parallel or converge toward each other instead of diverging from each other, as is the case with existing structures in which the jaws are directly connected at one end 100 without the interposition of an end member or the like. Thus, when a number of bunches of paper, each secured together by fasteners of the herein described construc- 105 tion, are lying one upon the other, the papers of one bunch will not catch in the fastener of another bunch. In other words, the jaws of the fastener lie smoothly or flatwise on the paper.

One of the jaws, for instance the jaw 3, 110 may be provided with a punch or prong 11 preferably stamped therefrom and which

projects toward the other jaw 2, the latter in such case being preferably formed with an aperture 12 for the reception of the end of said tongue. The aperture 12, generally speaking, may be in the form of a simple hole, as shown in Fig. 10 and in the preferred arrangement is bounded by a raised rib 13 with which the jaw 2 may be provided, said rib 13 being either continuous, as shown in Fig. 1 or interrupted, as illustrated in Fig. 10, or said aperture may correspond in shape to that of the prong 11 and thus, as shown in Figs. 1 to 9 inclusive, may be in the form of an elongated slot or rectangular opening to accommodate the flat prong 11 of the illustrated example. In such case, the slot or opening extends transversely of the space enclosed by the rib 13 and provides at least one web 14 within said rib 13, over which web the point of the punch or prong 11 may be clinched, if desired. The raised rib 13 is preferably arc-shaped in cross-section although this is not essential, it being understood that said rib may be omitted if desired. When the rib 13 is interrupted as shown in Fig. 10 a web is provided between adjacent ends of the interrupted web, over which web the prong may be clinched as described above.

Because provision is made in the improved fastener to define predetermined folding lines which are spaced from each other, the jaws or members 2 and 3 may be bent relatively to the end member 4 without material effort. When so bent, a relatively wide bend is provided in which a maximum number of sheets may be accommodated without forcing the same out of registry with each other and without causing the jaws 2 and 3 to diverge outwardly toward their free ends.

The fastener is economical and easy to produce, is easily applied to a plurality of sheets or detached therefrom and in its oper-

ative condition securely fastens the sheets together and yet makes intentional separation thereof a simple matter.

Various changes in the specific forms shown and described may be made within the scope of the claims without departing from the spirit of my invention.

What I claim is:—

1. A fastener struck up from sheet metal and consisting of an end member, jaws comprising integral extensions of said end member, said fastener being formed with recesses spaced apart to define parallel, spaced bending lines on which said jaws automatically bend relatively to said end member into opposed, spaced relation to each other, and a punch carried by one of said jaws.

2. A fastener struck up from sheet metal and consisting of an end member, jaws comprising integral extensions of said end member, said fastener being formed with closed recesses located entirely within the confines of the fastener and spaced apart to define parallel, spaced bending lines on which said jaws automatically bend relatively to said end member into opposed, spaced relation to each other, one of said jaws being provided with an aperture, a raised rib on said jaw following the periphery of said aperture, and a punch on the other jaw adapted to enter said aperture.

3. A fastener struck up from sheet metal and comprising connected jaws, one of which is provided with an opening, an interrupted raised rib on said jaw and extending about said opening to form a web between its adjacent ends and a prong on the other jaw adapted to be projected through said opening and clinched over said web.

In testimony whereof I have hereunto set my hand.

JAMES V. WASHBURN
